UNITED STATES PATENT OFFICE.

ROBERT C. BROMLEY, OF PITTSBURG, PENNSYLVANIA, ASSIGNOR TO THE
PITTSBURG VALVE AND MACHINE CO., LIMITED.

VALVE.

SPECIFICATION forming part of Letters Patent No. 593,412, dated November 9, 1897.

Application filed December 10, 1896. Serial No. 615,169. (No model.)

To all whom it may concern:

Be it known that I, ROBERT C. BROMLEY, a citizen of the United States, residing at Pittsburg, in the county of Allegheny and State of Pennsylvania, have invented or discovered a new and useful Improvement in Valves, of which the following is a full, clear, and exact description, reference being had to the accompanying drawings, forming part of this application, in which—

Figure 1 is a central vertical sectional view of a valve made in accordance with my invention. Fig. 2 is a similar view showing the plug turned to register with the openings in the valve-casing. Fig. 3 is a cross-section taken on the line III III of Fig. 1. Fig. 4 is a detail view in elevation of the lower portion of the plug. Fig. 5 is a view similar to Fig. 1, but showing a modified construction of adjusting device. Fig. 6 is a cross-section taken on the line VI VI of Fig. 5, looking upwardly. Fig. 7 is a similar view on the same line, looking downwardly.

My invention consists of an improvement in valves, and relates more particularly to the means for limiting the throw or travel of the valve-plug and for setting it tightly to its seat, together with means for adjusting and taking up the wear of such mechanism without re-

moval of the plug or any of the parts.

Referring to the drawings, 2 is the valve-casing, provided with suitable inlet and outlet ports and a central tapered seat 3. Within the casing is the plug 4, tapered to correspond to the seat 3 and provided with the lateral opening 5, coinciding with the inlet and outlet ports when in an open position, as shown in Fig. 2, and adapted to close such ports when turned at right angles, as in Fig. 1.

An extended stem 6 projects upwardly through a suitable stuffing-box forming a part of the valve-casing, in the bottom of which is placed a suitable gasket 7, while at the bottom the plug is provided with a short extension 8 of reduced diameter, terminating in a screw-threaded teat 9.

The base of the valve-casing is flanged, and secured thereto by bolts is a lower head 10, in the center of which is a polygonal opening 11 forming a pocket for a nut 11, screwed upon the teat 9 and held against rotation by the polygonal pocket in the head 10. A follower

12 is screwed into the under center of the head 10 and forms a bottom for the nut 11, so that when the plug is rotated in the direction of the arrow, Fig. 3, the nut will be thrown down against the follower, as shown in Fig. 1, and a pressure will be exerted upwardly upon the plug to bind it to its seat.

By means of the very delicate adjustment of which the follower 12 is capable the binding action of the plug can be so accurately adjusted as to occur only at the end of the throw, and at the same time will limit the throw by preventing further rotation due to such binding action. Upon reversing the movement of the plug the binding pressure will be immediately released. In order to hold the plug to its seat at all times with a moderate pressure, ports 13 are made, communicating with the central opening 5 and leading upwardly and downwardly, supplying pressure upon the shoulders 14 15 of the plug, the lower of which (in Fig. 5 the upper) by reason of its greater area will receive a greater pressure, and such excess of pressure will serve to always keep the valve to its seat.

A packing-ring 16, interposed between the flanged base and head 10 and embracing the extension 8, makes a tight joint against leakage.

In Fig. 5 I have shown a modified construction in which the plug is tapered downwardly, and the casing is provided with an externally-threaded extension 17, through the center of which the threaded teat 9 projects, and having a bearing-face 18, upon which the nut 11 bears. A hood 19 is made with a polygonal pocket 20, adapted to embrace the nut and prevent its rotation, while the hood is held in position by a flanged union 21, screwed upon the threaded extension 17. The lower edge of the extension 17 and the upper surrounding edge of the hood 19 are provided with similar serrations or corrugations 22 23, interfitting, and when clamped together by the union 21 the hood 19 is effectually prevented from turning. By partially unscrewing the union the hood 19 may be rotated, and with it the nut 11, for adjustment or taking up wear, whereby the nut may be adjusted to any desired degree of pressure upon the threaded teat 9, so as to very accurately regulate its downwardly-exerted pull upon the plug.

The operation of my device is obvious, and its especial advantages of nicety of adjustment and means for taking up wear will commend it to those accustomed to use valves for high pressures.

I am aware that valves have been made with threaded stems and nuts thereon held against rotation and am familiar with the patents issued to H. E. Keyes July 30, 1895, for such devices; but my invention possesses features of novelty and advantage not heretofore introduced in devices of this character. It will be observed that the adjustments of the nuts can be easily and quickly accomplished without entirely removing any of the parts, such adjustment being made by means of the outer inclosing and embracing portions of the valve-case, as has been described, and such features of advantage I consider important and valuable.

A further modification of my invention, employing the constructions of Figs. 1 and 5, respectively, above and below the plug, whereby it would be limited as to its throw in either direction, can be made with advantage, and such a construction is contemplated by me and is within the scope of the present invention.

Having described my invention, what I claim is—

1. A valve having a chambered tapered plug, provided with a valve-stem and an externally-threaded extended teat on the opposite end of the plug, a nut engaging the threaded teat, and an adjustable backing for the nut, substantially as set forth.

2. A valve having a chambered tapered plug, provided with a valve-stem and an externally-threaded extended teat on the opposite end of the plug, a polygonal nut engaging the threaded teat, a surrounding holder for the nut to prevent its rotation, and an adjustable follower mounted in the surrounding holder and forming a backing for the nut, substantially as set forth.

3. A valve having a chambered tapered plug, provided with a valve-stem and an externally-threaded extended teat on the opposite end of the plug, a polygonal nut engaging the threaded teat, a surrounding holder for the nut to prevent its rotation, and a follower, screw-threaded into an extension of the surrounding holder and forming a backing for the nut, substantially as set forth.

In testimony whereof I have hereunto set my hand this 2d day of October, 1896.

ROBERT C. BROMLEY.
